SHOE MACHINE

Bernhardt Jorgensen, Marblehead, Mass., assignor to United Shoe Machinery Corporation, Flemington, N. J., a corporation of New Jersey

Application May 15, 1942, Serial No. 443,097, which is a division of application Serial No. 377,347, February 4, 1941. Divided and this application January 29, 1943, Serial No. 473,936

3 Claims. (Cl. 12—51)

This invention relates to shoe machines, this application being a division of an application Serial No. 443,097, filed on May 15, 1942, which is a division of an application Serial No. 377,347, filed on February 4, 1941. An object of the invention is to provide means for trimming from the toe end of a multi-ply upper on a last the margin of one or more inner layers of the upper materials while leaving a margin of the outer layer to be lasted inwardly over an insole on the last, and means for applying cement to the shoe for thereafter securing the margin of the outer layer to the insole; and the invention is herein illustrated as embodied in such a combination of means forming part of the machine shown and described in the above-mentioned application Serial No. 377,347, which is a machine for lasting the toe ends of shoes. It is to be understood, however, that the invention is not limited to the illustrative embodiment or to structure forming part of a lasting machine.

For the purposes in view, the invention provides an upper-trimming device and a cement-applying device which are movable as a unit to bring the different devices alternately into positions to operate on a shoe. The construction herein shown comprises a carrier common to both the devices and movable about an axis extending heightwise of the shoe to position the cement-applying device opposite the bottom of the toe end of the shoe after the upper-trimming device has been so positioned, the carrier being movable axially heightwise of the shoe to carry each device toward the shoe. In accordance further with the illustrative disclosure, cylinder-and-piston mechanisms are provided for imparting respectively to the carrier its different movements by fluid pressure.

The novel features of the invention, including various novel details of construction and combinations of parts, will now be more particularly described with reference to the accompanying drawings and thereafter pointed out in the claims.

In the drawings,

Fig. 1 is mainly a plan view of a portion of the machine in which the invention is herein illustrated as embodied;

Fig. 2 is a section on the line II—II of Fig. 1;

Fig. 3 is a section on the line III—III of Fig. 1, on an enlarged scale;

Fig. 4 is a section on the line IV—IV of Fig. 3;

Fig. 5 is a vertical sectional view of a portion of the side upper-trimming means;

Fig. 6 is a section on the line VI—VI of Fig. 55

1, on an enlarged scale, showing the cement-applying means;

Fig. 7 is a view partly in elevation and partly in section, illustrating the relation to the shoe of the parts that operate thereon at a time in the cycle immediately prior to the upper-trimming operation;

Fig. 8 is mainly a plan view showing the parts in the positions which they occupy at the same time in the cycle as in Fig. 7;

Fig. 9 is mainly a vertical sectional view showing certain parts as they appear at the beginning of the side upper-trimming operation;

Figs. 10, 11 and 12 are sectional views illustrating progressively the positions of the parts at other times thereafter in the operation of the machine; and

Fig. 13 is a view partly in plan and partly in section, showing certain parts at the same stage in the cycle as in Fig. 12.

The machine shown in the above-mentioned application Serial No. 377,347, in which the present invention is herein illustrated as embodied, is a power-operated lasting machine having means for lasting the toe end of a shoe positioned bottom upward. The shoe is thus positioned in proper relation to the lasting means by a member 2 (Fig. 7) which engages the bottom of the toe end of the insole and by a plurality of pins 4 which extend through holes in the insole into holes provided in the last. The operator mounts the shoe and last on the pins 4 with the insole in engagement with the member 2 prior to the starting of the cycle of power operations of the machine. After the starting of the machine a toe rest 6 and an instep support 8 are moved upwardly to clamp the shoe against the member 2 and to support it thereafter against downward movement during the operation of the machine. To assist also in supporting the shoe against lengthwise movement, a heel rest 10 is moved into engagement with the heel-end face of the shoe. The shoe having thus been positioned and supported, a plurality of grippers, comprising a toe-end gripper 12 and side grippers 14 (Fig. 8), which grip the margin of the several layers of the toe-end portion of the upper, are moved in outward directions lengthwise and widthwise of the shoe respectively to pull the upper and thus to assist in shaping it properly over the toe end of the last. Arranged to cooperate with these grippers in the lasting operation are a flexible toe former 16, which embraces the toe end of the shoe, and a pair of toe-embracing wipers 18. The toe former and the

wipers are moved as a unit heightwise of the shoe to cause the toe former to wipe the upper upwardly to the edge of the insole while it is held under tension by the gripper, as illustrated in Fig. 7. Surplus marginal material is next trimmed from all but the outer layer of the toe-end portion of the upper by trimming means, hereinafter described, the grippers releasing the upper to make way for the trimming means. Cement is then applied to the toe end of the shoe for securing the margin of the outer layer of the upper to the insole, and the wipers 18 are operated to wipe the margin of the outer layer inwardly over the insole. It will be understood that the nature of the operations thus briefly outlined and the construction of the machine as a whole are fully disclosed in the previously mentioned application Serial No. 377,347.

For trimming the upper there is provided an upper-trimming device indicated generally by the reference character 20 (Fig. 1), associated with which is a cement-applying device indicated generally by the reference character 22. Both these devices are supported on a carrier 24 clamped on a vertical hollow post 26. This post is guided for vertical movements and for turning movements in a cylinder 28 (Fig. 3) inserted in a tubular portion 30 of the frame of the machine and in another bearing (not herein shown) below the cylinder 28. By the vertical movements of the post the trimming device and thereafter the cement-applying device are moved downwardly each into position to operate on the shoe, and by the turning of the post the carrier 24 is swung to carry the different devices into positions where they are over the toe end of the shoe. Initially the carrier occupies the position in which it is shown, with the trimming device over the shoe, this position of the carrier being determined by engagement of a bumper 32 (Fig. 1) with a portion 34 of the frame of the machine. The other position of the carrier, when the cement-applying device is over the shoe, is determined by engagement of a bumper 36 on the carrier with another portion (not shown) of the frame. Swinging movement of the carrier into the last-mentioned position is effected by a piston 38 movable in a cylinder 40 fast on the frame, the piston being connected by a link 42 to a pin 44 mounted on an arm 46 which is connected to the post 26 for turning it but relatively to which the post may move in vertical directions. In communication with the cylinder 40 is a pipe line 48 leading to a source of supply of operating fluid and to valve mechanism whereby the admission of fluid to the cylinder and the exhaust of fluid therefrom are controlled automatically in the cycle of operations of the machine, as fully disclosed in the previously mentioned application Serial No. 377,347. The link 42 extends beyond the pin 44, and connected to the extended portion of the link and to the cylinder 40 is a spring 50 which swings the carrier 24 to its initial position determined by engagement of the bumper 32 with the frame portion 34 when the fluid is permitted to exhaust from the cylinder.

The upper end of the hollow post 26 is closed by a plug 52 (Fig. 3) and a disk 54 fastened to this plug serves as a holder for packing 56. The upper end portion of the post serves, therefore, as a piston in the cylinder 28, and by fluid admitted to the upper end of the cylinder through a pipe line 58 downward movement is imparted to the post to carry the trimming device and

the cement-applying device each into position to operate on the shoe. It will be understood that the pipe line 58 leads to the source of fluid supply and that the admission and exhaust of fluid to and from the cylinder 28 are controlled by appropriate automatic valve mechanism. The downward movement of the post is effected against the resistance of a spring 60 therein which bears at its upper end against the plug 52 and acts to return the post to its uppermost position when fluid is permitted to exhaust from the cylinder 28, the upward movement of the post being limited by engagement of a fibre bumper 62 supported on the hub of the carrier 24 with the lower end of the tubular portion 30 of the frame. The limit of the downward movement of the post, to position the trimming device and the cement-applying device in proper relation to the shoe heightwise thereof, is determined by means not herein shown but disclosed in the last-mentioned application.

The upper-trimming device 20 comprises a middle knife 64 (Figs. 3 and 8) which is curved in general similarity to the curvature of the edge of the insole around the end of the toe and is movable lengthwise of the shoe toward the toe-end gripper 12, and two side knives 66 movable laterally of the shoe toward the side grippers 14 in paths curved about a vertical axis located opposite the end of the toe. The cutting edges of the several knives, in operating on the upper, move in a plane parallel to the top faces of the wipers and spaced from these faces a distance substantially equal to the thickness of the outer layer of the upper materials, so that as the marginal portions of the different layers are cut over the wipers the knives sever the surplus marginal material of the inner layer or layers while leaving a margin of the outer layer to be lasted inwardly over the insole. As illustrated, the top faces of the wipers (Fig. 7) are positioned at the time of the upper-trimming operation somewhat above the plane of the bottom face of the toe end of the insole, to leave enough of the inner layer or layers to overlap the extreme marginal edge of the insole when the wipers thereafter wipe the outer layer inwardly. It will be understood that the toe end of the upper materials usually comprises at least three layers, including a lining and a toe box in addition to the outer layer, but for convenience of illustration the drawings show only the lining in addition to the outer layer. As shown in Fig. 8, the shoe is preferably prepared for the operation of the machine by slitting the margin of the upper materials at the sides of the toe forwardly of the side pulling-over tacks, to facilitate turning of the margin of the toe-end portion of the materials outwardly in parallel relation to the plane of the wipers, and the knives act to sever completely the surplus margin of the inner layer or layers from the rest of the upper materials. The operation of the trimming means is such that the side knives 66 act on the upper prior to the middle knife 64, the grippers maintaining their hold on the upper until these side knives have started their trimming operation, as illustrated in Fig. 9, whereupon the several grippers open and are moved farther outwardly to provide clearance for the knives. After the side knives have completed their operative movements the middle knife 64 acts, as illustrated in Figs. 10 and 11, to complete the severing of the surplus material.

Each side knife 66 is secured to a knife holder

68 (Figs. 1, 3 and 5) the upper portion of which is curved in a horizontal plane (Fig. 1) and is provided with flanges movable along curved guideways 70 in the carrier 24, these guideways being curved, as above suggested, about a vertical axis located opposite the end of the toe of the shoe. The flanges are supported underneath by gibs 72 (Fig. 3). Each knife 68 is adjustable heightwise of the shoe relatively to its holder 66, and is held in adjusted position by a clamping screw 74 threaded in the knife and extending through a slot 76 in the holder. A fine adjustment of the knife is facilitated by the provision of a screw 78 which is threaded in a lug on the holder 66 and arranged to bear on the upper edge of the knife. The two holders 66 are connected by links 80 (Fig. 1) to the outer ends of levers 82 which are pivotally mounted at their inner ends on studs 84 (Fig. 4) on the carrier 24. Studs 86 connecting the links 80 to the holders 66 extend through slots 88 in the carrier 24. The levers 82 are controlled by a slide 90 (Fig. 4) movable lengthwise of the shoe along guideways on the carrier 24 and held on its guideways by a pair of gibs 92 and another pair of gibs 94. Formed on the opposite side edges of this slide are cam faces 96 engaged by rolls 98 mounted on the levers 82. Accordingly, upon rearward movement of the slide 90, i. e., movement toward the left in Fig. 4, the cam faces 96 act on the rolls 98 to swing the levers 82 outwardly about the studs 84 and thus to impart operative movements to the side knives 68. After these knives have thus been operated the rolls are engaged by parallel side edges 100 of the slide 90 to permit further movement of the slide while the side knives remain stationary. These knives are returned to their initial positions, upon reverse forward movement of the slide 90, by engagement of a crossbar 102 fast on the slide with the rolls 98.

Operative rearward movement is imparted to the slide 90 by a fluid-operated piston 104 mounted in a cylinder 106 which is integral with the carrier 24, the piston being connected by a link 108 to one arm 110 of a three-armed lever 112 mounted to swing about a pin 114 supported in upwardly extending webs of the carrier 24. A second arm 116 of the three-armed lever is connected by a link 118 to a pin 120 mounted in lugs on the slide 90. Accordingly, upward movement of the piston 104 serves to move the slide 90 in a rearward direction, this movement being limited by engagement of a lug 122 on the arm 116 with a face 124 on the cylinder 106. Return movement of the slide 90 is effected by springs 126 connected to a pin 127 on the carrier 24 and to short arms 128, one of which is shown in Fig. 3, integral with the three-armed lever 112. Such return movement of the slide is limited by engagement of the crossbar 102 thereon with the rolls 98, the latter engaging the cam faces 96 on the slide. Fluid is admitted to the cylinder 106 from a pipe line 130 (Fig. 1) a portion of which is flexible to permit the swinging movements of the carrier 24. Admission and exhaust of fluid to and from the cylinder are controlled by an appropriate automatically operated valve (not herein shown), as disclosed in the previously mentioned application Serial No. 377,347.

The middle knife 64 is supported on the lower front end of a curved arm 132 which extends rearwardly and is pivotally mounted at its rear end for swinging movements heightwise of the shoe on the pin 128. The knife is adjustable relatively to this arm and is secured in adjusted po-

sition by a clamp screw 134 threaded in the knife and extending through a slot 136 in the arm. Two set screws 138 (Figs. 1 and 8) threaded in the arm and engaging the upper surface of the knife are provided to assist in obtaining a fine adjustment of the knife about an axis extending lengthwise of the shoe. The front end of the arm 132 is held initially upraised by a spring 140 connected to the arm above the pivot pin 128 and to a pin 142 on the slide 90. The initial position of the arm is determined by engagement of a lug 144 on its rear end with the top face of the slide 90, as illustrated in Figs. 3 and 4. It will be evident that the arm 132 is carried rearwardly by the slide 90, but it remains upraised until the side knives 68 have been swung substantial distances away from each other. The arm is then swung downwardly to carry the knife 64 to the same plane as the side knives, and by further movement of the slide 90 thereafter the knife 64 is moved rectilinearly to complete the upper-trimming operation. For thus swinging the arm downwardly there is provided a lever 146 pivotally mounted on a pin 148 in the upstanding web portions of the carrier 24 and provided with a roll 150 arranged to engage a plate 152 fast on the arm. A third arm 154 of the three-armed lever 112 carries a roll 156 which by engagement with a rearwardly extending arm 158 of the lever 146 holds this lever initially with the roll 150 retracted rearwardly beyond the plate 152. As the three-armed lever 112 receives its operative movement the roll 156 is carried downwardly along the rear face of the lever 146 and by engagement with a cam face 160 on this lever swings it in a forward direction as the arm 132 is being carried rearwardly. This causes the roll 150 to act on an inclined edge 162 of the plate 152 to impart a quick downward movement to the arm 132, after which the roll engages the top face of the plate to maintain the knife 64 at the proper height during its action on the upper materials. At this time the lever 146 is held stationary by engagement of the roll 156 with a face 164 of the lever which is curved on an arc concentric with the axis of the pin 114. As the arm 132 is swung downwardly a lug 166 extending upwardly from the slide 90 enters a recess 168 in the arm to insure by engagement with the side walls of this recess that the arm is held properly positioned laterally. To insure against damage in case the arm 132 should be swung accidentally downward when the machine is idle, a lug 170 (Fig. 1) on the arm is arranged to engage a lug 172 formed on one of the gibs 94.

It is desirable during the upper-trimming operation to hold the margin of the toe end of the insole down on the last out of the way of the trimming knives. The machine is accordingly provided with a holdown 174 comprising a rod curved similarly to the toe end of the insole and having upwardly extending portions 176 mounted in brackets 178 fast on the carrier 24. The curved portion of the rod thus engages the insole between the latter and the paths of movement of the trimming knives. The upwardly extending portions 176 of the rod are adjustable vertically in upwardly extending tubular portions of the brackets 178, these tubular portions being split and encircled by split clamps 180 (Fig. 1) which are contracted by suitable screws to retain the holdown in adjusted position. It will be understood that the holdown is moved into engagement with the insole by the downward movement of the carrier 24.

The cement-applying device 22, as herein shown, is so constructed as to adapt it for use to apply thermoplastic cement maintained by heat in a liquid condition to the insole to fasten the toe end of the upper to the insole, although cement of a different kind may be used if desired. For this purpose the carrier 24 serves as a support for a casting 234 (Figs. 1 and 6) having therein a cement-containing chamber 236. The casting 234, which thus serves as a cement receptacle, is supported directly by means of rods 238 and 240 on the front ends of upper and lower pairs of parallel links 242 and 244 the rear ends of which are mounted respectively on rods 246 and 248 on the carrier 24. The two upper links 242 are connected together by a web 250, and threaded in an ear 252 (Fig. 2) on this web is a screw 254 the lower end of which is controlled by a compression spring 256 mounted in a socket in the carrier 24. This spring tends to swing the links 242 and 244 downwardly, the limit of such downward movement of the links and of the casting 234 being adjustably determined by a screw 258 which is threaded in an ear 260 on one of the links 242 and is arranged to engage a vertical face 262 on the carrier 24. It will be understood that the spring 256 is yieldable to permit any further downward movement of the carrier 24 which may take place after downward movement of the casting 234 is stopped by the shoe in the manner hereinafter explained. To maintain the cement in the chamber 236 in a liquid condition the casting 234 is heated by electrical heating units 264 (Fig. 1) mounted in bores therein.

Mounted in a bore in the lower end of the casting 234 is a cylindrical upwardly extending portion of a block 266 (Fig. 6) the lower portion of which is of horseshoe shape, as illustrated in Fig. 13, and is provided with two bores 268 communicating with each other through a chamber 270. This horseshoe-shaped portion of the block is arranged to engage the marginal portion of the toe end of the insole, as illustrated in Figs. 12 and 13, and extending through it from the bores 268 and the chamber 270 are holes 272 through which cement is applied to the insole. The chamber 270 communicates through an upwardly extending bore 274 in the block 266 with a chamber 276 in the casting 234, and this chamber is arranged to communicate with another chamber 278 from which a passage 280 leads to the cement-containing chamber 236. Leading upwardly from the chamber 278 is a bore 282 in the casting 234, in which is mounted a pump plunger 284. Normally closing the passage 280 is a ball valve 286 held on its seat by a spring 288 mounted between the valve and the lower end of the plunger 284, and normally closing communication between the chamber 276 and the chamber 278 is a ball valve 290 held on its seat by a spring 292. When the plunger 284 is moved upwardly it draws cement past the valve 286 into the chamber 278, and when it is moved downwardly it forces cement past the valve 286 into the chamber 276 and thence through the passage 274 and the holes 272 to deliver it on the toe end of the insole. The plunger 284 is moved downwardly to deliver the cement in the manner described as a result of the downward movement of the carrier 24 to carry the cement-applying device toward the shoe by the action of means not herein fully shown but disclosed in the previously mentioned application Serial No. 377,347.

As also fully disclosed in that application, the

block 266 is wedged upwardly with the casting 234 by the action of the wipers and the upper thereon against the resistance of the spring 256 when the wipers wipe the margin of the outer layer inwardly over the insole.

The manner of operation of the machine, in so far as it is of interest with reference to the present invention, will now be briefly summarized. After the shoe has been presented in the position determined by the member 2 and the pins 4 and after the starting of the power operation of the machine the toe rest 6, the instep support 8 and the heel rest 10 are moved into the shoe-supporting positions in which they are shown in Fig. 7. Shortly after the beginning of the cycle of operations also the grippers 12 and 14 are operated to pull the upper in outward directions, and while these grippers are holding the upper under tension the toe former 16 and the wipers 18 are moved upwardly to cause the toe former to wipe the upper heightwise of the last, the parts then occupying the positions in which they are shown in Fig. 7. In the meantime the carrier 24 has been moved downwardly to carry the upper-trimming means into operative position in response to the admission of fluid to the cylinder 23. Immediately after the wiping of the upper heightwise of the last fluid is admitted to the cylinder 106 to operate the three-armed lever 112 and thereby to impart rearward movement to the slide 90. As this slide begins its rearward movement its cam faces 96 act on the rolls 98 to impart outward swinging movements to the side trimming knives 66. Immediately after these knives begin to act on the upper (Fig. 9) the several grippers are opened to release the upper and are moved out of the paths of the knives. It will be understood that the knives, moving in a plane parallel to the wipers 18, cut through all but the outer layer of the spread upper materials which is next to the wipers. As the side knives are being operated as described, bodily rearward movement is imparted by the slide 90 to the arm 132 which carries the middle knife 64, and upon engagement of the roll 156 on the three-armed lever 112 with the cam face 160 of the lever 146 the latter is swung in a forward direction to cause its roll 159 to act on the inclined edge 162 of the plate 152 and thereby to swing the arm 132 downwardly to position the middle knife 64 in the same plane as the side knives. By the time, therefore, when the side knives have completed their operative movements the middle knife is in position to act on the upper in response to further rearward bodily movement of the arm 132, the middle knife being maintained in the proper plane by engagement of the roll 156 with the top face of the plate 152. In this manner the middle knife completes the upper-trimming operation as illustrated in Figs. 10 and 11. As soon as the trimming operation is completed fluid is released from the cylinder 23 to permit the carrier 24 to be moved upwardly by the spring 60, and at approximately the same time fluid is released from the cylinder 106 to permit the slide 90 to be returned by the springs 126 and the arm 132 to be swung upwardly by the spring 140. Thereafter fluid is admitted to the cylinder 40 to swing the carrier 24 into the position in which the cement-applying means 22 is over the shoe. Admission of fluid once more to the cylinder 23 then causes the carrier 24 to move downwardly to carry the cement-applying means into engagement with

the shoe, as illustrated in Fig. 12, and to apply cement to the shoe. Thereafter, in the course of the cycle of operations the wipers 18 are operated and the carrier 24 is moved upwardly and is swung back to its initial position in proper time relation to return movements of other parts of the machine.

Having described the invention, what I claim as new and desire to secure by Letters Patent of the United States is:

1. In a shoe machine, the combination with a support for a last having shoe materials comprising an insole and a multi-ply upper thereon, of an upper-trimming device arranged to sever from the toe end of the upper materials the margin of one or more inner layers of the materials while leaving a margin of the outer layer to overlap the insole, and a device for applying cement to the shoe for securing the margin of the outer layer to the insole, the upper-trimming device and the cement-applying device being movable as a unit to bring the different devices alternately into positions to operate on the shoe.

2. In a shoe machine, the combination with a support for a last having shoe materials comprising an insole and a multi-ply upper thereon, of an upper-trimming device arranged to sever from the toe end of the upper materials the margin of one or more inner layers of the materials while leaving a margin of the outer layer to overlap the insole, a device for applying ce-

ment to the shoe for securing the margin of the outer layer to the insole, and a carrier common to said upper-trimming device and cement-applying device and movable to position the cement-applying device opposite the bottom of the toe end of the shoe after the upper-trimming device has been so positioned, said carrier being also movable heightwise of the shoe to carry each device toward the shoe.

3. In a shoe machine, the combination with a support for a last having shoe materials comprising an insole and a multi-ply upper thereon, of an upper-trimming device arranged to sever from the toe end of the upper materials the margin of one or more inner layers of the materials while leaving a margin of the outer layer to overlap the insole, a device for applying cement to the shoe for securing the margin of the outer layer to the insole, a carrier common to said upper-trimming device and cement-applying device and movable about an axis extending height-wise of the shoe to position the cement-applying device opposite the bottom of the toe end of the shoe after the upper-trimming device has been so positioned, said carrier being also movable axially heightwise of the shoe to carry each device toward the shoe, and cylinder-and-piston mechanisms for imparting respectively to the carrier its different movements by fluid pressure.

BERNHARDT JORGENSEN.
